UNITED STATES PATENT OFFICE.

LARS RÖD, OF MONTREAL, QUEBEC, CANADA.

NON-REFILLABLE BOTTLE.

No. 881,959.

Specification of Letters Patent. Patented March 17, 1908.

Application filed March 14, 1907. Serial No. 362,434.

To all whom it may concern:

Be it known that I, LARS RÖD, a subject of the King of Great Britain, residing at Montreal, Canada, have invented certain new and useful Improvements in Non-Refillable Bottles; and I do declare the following to be a full, clear, and exact description of the invention, such as will enable others skilled in the art to which it appertains to make and use the same.

10 This invention relates to what are known as "non-refillable" bottles, and has for its object to provide a device of this kind which can be readily applied to the ordinary bottle, and which will render it impossible to refill 15 the same after its contents have been removed.

In the accompanying drawings, which illustrate the invention,—Figure 1 is a longitudinal, sectional view of the upper end of a 20 bottle provided with my improved non-refilling attachment in place therein; Fig. 2 is a bottom plan view of the lower end of the attachment; Fig. 3 is a top plan view of the same; and Fig. 4 is a plan view of one of the 25 floors or partitions in the device.

Referring more particularly to the drawings, 1 indicates a bottle which can be formed in any desired manner, except that its neck, 2, is provided with an annular recess, 3, near 30 its lower end.

My attachment consists preferably of a frusto-conical body, 4, which can be formed from glass, porcelain, or metal. Its lower end is provided with a plate, 5, which is 35 perforated at 6 and 7, and is adapted to be formed upon or secured to the lower end of the body in any desired manner.

Secured to the lower face of the plate, 5, as by means of loops or staples, 5', are springs, 40 8, which are adapted to engage with the recess, 3, when the device has been placed in position and thereby prevent the removal of the same. A tube or pipe, 9, extends upward through the opening, 7, to any desired height.

45 A lever, 10, is passed through the plate, 5, and pivotally secured thereto as by means of ears, 11, and has a cork or stopper, 12, upon one end and a flat disk or valve 13, at the other. The cork and disk are so related to 50 each other that when the valve is forced upon its seat so as to cover the opening, 6, as by means of a ball, 14, the cork, 12, will be forced into the lower end of the tube, 9, and thereby close the same. The ball, 14, is 55 cured in its desired position by means of a cage, 15, which is preferably conical and ex-

tends from the plate 5, upward substantially to a floor, or partition, 16. The valve, 13, is preferably provided with radially extending wings, 17, which are adapted to be engaged by the ball and thereby assist in holding the valve 13 upon its seat. An upwardly extending spring, 18, is connected with the lever, 10, at its pivot point so as to engage with the pipe 9 when the lever is swung upon its pivot 60 and thereby prevent the valve 13 from moving so far from its seat as to permit the ball 14 passing down underneath it through the opening 6 into the bottle. Above the cage, 15, are a series of inwardly extending floors 70 or partitions, 16, which preferably have their inner edges cut away or recessed as shown at 19. By arranging the partitions in this manner, the liquid can readily pass through the passage formed thereby, but it will be impossible for an object, as a wire, to be inserted 75 into the neck of the bottle past said partitions, and thereby open the perforations 6 and 7, to permit of the introduction of any liquid after the contents of the bottle have 80 been removed.

In securing my attachment to a bottle, the springs, 8, are compressed so as to enter the neck of the bottle, and the device is forced downwardly until the recess, 3, is reached, 85 when the springs will instantly expand and thereby lock the device in position. A filling, 20, as of cork, is then inserted between the neck of the bottle and the device, and a seal or binder, 21, as of plaster of paris, 90 cement, or other suitable material, is then filled in above the cork to the top of the neck. A flanged disk, 22, is then seated over the seal, 21, with its edges bent down so as to engage with the neck of the bottle and prevent 95 its removal, and its body portion adapted to receive letters or characters. A removable cap, 23, is then placed upon the projecting portion, 24, of the body, 4, and the closing of the bottle is complete.

100 In emptying the bottle, it is turned into a horizontal position with the valve, 13, occupying its lowest point and the cork, 12, being in the opening, 7, and the bottle being preferably provided with instructions, as 105 "This side up when emptying" placed upon the side of the bottle which will be uppermost when said parts occupy the above described position.

When the device is formed from glass, or 110 porcelain, the partitions, 16, are preferably formed integral therewith, but when it is

formed from metal the partitions are secured in place as by solder, the upper or smaller one being secured first and the others in succession, and, after the ball and cage have 5 been placed in position, the bottom plate, 5, is secured thereto either permanently or removably, as by screw threads, in the ordinary manner.

When the bottle is being emptied, the ball 10 will roll off of the valve into the forward or upper portion of the cage, and the liquid will force the valve off its seat and escape past the partitions as above described, the air entering the bottle through the air pipe, 9, 15 to take the place of the liquid that runs out. After as much of the contents have been emptied as desired, the bottle is returned to its normal position, which will cause the ball to roll down upon the valve, 13, or either 20 one of the wings 17 and thereby cause said valve to close said opening and also cause the cork, 12, to be seated in the lower end of the pipe, 9, and thus prevent the access of air to the contents of the bottle, even though the 25 cap 23 should not be replaced. The slight amount of liquid that will be retained by the lower partitions will also flow down onto the plate 5 and thereby assist in closing the opening 30 therein.

Upon attempting to refill the bottle by placing it on its side in a tub filled with liquid, the ball will close the openings, 6 and 35 7, and thereby prevent the entrance of the liquid, and by holding the bottle in an inverted position, the cork, 12, which is preferably made slightly heavier than the valve, 13, will cause the lever 10 to be swung upon its pivot so as to close the pipe, 9, and the 40 opening 6, and thereby prevent the entrance of liquid in that manner.

Having described my invention, I claim:

1. In a non-refillable bottle, a bottle provided with an annular recessed neck, a frusto-conical body within the neck provided with a tortuous passage and having its lower end perforated, means for closing said perforations, and springs for entering said recesses and preventing the removal of the body.
2. In a non-refillable bottle, a frusto-conical hollow body having a perforated plate at one end and a plurality of oppositely extending substantially half moon shaped partitions toward the other end, pivotally mounted 55 stoppers for said perforations, and a weight for closing the same.
3. In a non-refillable bottle, a substan-

tially frusto-conical hollow body provided with a perforated plate at one end, and having oppositely extending alternately arranged half moon projections in the remaining portion, a lever passed through said plate and pivotally mounted therein, the ends of said lever being provided with means for closing said perforations, and a ball for 60 engaging with one of said means.

4. In a non-refillable bottle, a substantially frusto-conical hollow body provided with a perforated plate a bent lever passed through said plate and pivotally mounted 70 therein, the ends of said lever being provided with means for closing said openings, a pipe connecting with one of said openings, a spring connected with said lever at its pivot point in position for engaging the said pipe, 75 a ball in said body for engaging with one of said closing means, and oppositely extending alternately arranged projections in the upper portion of said body.

5. In a non-refillable bottle, a substantially frusto-conical hollow body provided with a perforated bottom, a pipe communicating with one of said openings, a lever pivotally mounted in said bottom, one end of which is provided with a cork for closing the 80 pipe, and the other is provided with a winged valve for closing the other opening, a spring connected with the lever at its pivot point in position for engaging with said pipe, a cage upon said bottom, a ball in the cage adapted 85 to rest upon said valve or either of the wings, and oppositely extending alternately arranged half moon projections in the remaining portion of said body.

6. The combination with a bottle provided 95 with an annularly recessed neck, of a frusto-conical hollow body seated therein, said body being provided with a perforated bottom, springs on said bottom for engaging 100 with said recess, means for closing said openings, means for forming a tortuous passage in the upper portion of said body, a cork filler between the body and the neck above said recess, a seal above the cork, a flanged plate over the seal and the upper end of the 105 neck, and a cap upon the projecting end of said body.

In testimony whereof I have hereunto set my hand in presence of two subscribing witnesses.
